UNITED STATES PATENT OFFICE.

CLEMENT C. CLAWSON, OF NEWARK, NEW JERSEY.

POWDER-DISTRIBUTER.

SPECIFICATION forming part of Letters Patent No. 609,572, dated August 23, 1898.

Application filed November 16, 1897. Serial No. 653,706. (No model.)

To all whom it may concern:

Be it known that I, CLEMENT C. CLAWSON, a citizen of the United States, residing at Newark, in the county of Essex and State of New Jersey, have invented certain new and useful Improvements in Powder-Distributers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to a novel device for spreading or distributing powder upon the bristles of brushes or the like, and is adapted more especially for use in distributing tooth-powders upon brushes to be used for the purpose of brushing the teeth.

The invention therefore has for its primary object to provide a device for the purposes above stated combining in its construction a suitable receptacle for the reception of the powder, the receptacle having an outlet-opening, a supporting frame or base, and means arranged and operating to normally close the outlet-opening in the receptacle, but being adapted to be removed from said opening when a tooth or other similar brush is placed beneath the powder-receptacle, to permit of a sufficient quantity of powder to be distributed upon the bristles of the brush.

A further object of the invention is to provide in connection with the powder-containing receptacle a supporting frame or base and a rest in the frame or base for the brush, an oscillating slide adapted to normally close the outlet-opening in the powder-receptacle, but being adapted to be removed from said opening by the action of the brush as it is passed onto the rest in the frame or base, and a means within said receptacle to be actuated at the same time with the oscillating slide and to cause the powder to be forced through the outlet-opening in the receptacle.

A further object of this invention is to provide a simple and inexpensive device for the purposes stated which shall be ornamental as well as useful and can be effectively used on the dresser without the least danger of spilling any of the powder, and, furthermore,

the parts being arranged to permit but a certain quantity of powder to be deposited upon the brush, thereby preventing the use of too much powder upon the brush, which causes a waste of the powder and very often is deleterious to the teeth.

The invention therefore consists in the novel construction of powder-distributing device herein set forth, and also in the novel arrangements and combinations of parts and details of the construction thereof, all of which will be more fully described in the accompanying specification and finally embodied in the clauses of the claim.

The invention is clearly illustrated in the accompanying drawings, in which—

Figure 1 is a side view, and Fig. 2 a front end view, of a powder-distributer embodying the principles of my present invention; and Fig. 3 is a top view of the same with the cover or lid to the powder-receptacle removed. Fig. 4 is a side view of the powder-receptacle and its oscillating slide, the supporting frame or base of the device being represented in longitudinal vertical section. Fig. 5 is a longitudinal vertical section of the powder-distributer, taken on line α in Fig. 3, the movable parts of the device being represented in their initial or inoperative positions; and Fig. 6 is a similar view of the several parts of the device, representing the movable parts in their operated positions to distribute the powder upon the bristles of a brush. Fig. 7 is a perspective view of the oscillating slide and a frame with which it is connected.

Similar letters of reference are employed in all of the above-described views to indicate corresponding parts.

In said drawings, a indicates a suitable supporting frame or base, which is preferably closed on its opposite sides a' and a'' and at its back a^3 , substantially as illustrated. The front of said frame or base is provided with an opening a^4 in the closed part a^5 , said opening and closed part forming a suitable rest a^6 for the reception of a brush b as it is passed in and out of said opening for the reception of the powder from the powder-receptacle, as clearly indicated in Fig. 6.

The powder-receptacle is indicated by the reference-letter c and is made from a pair of convex shells, of metal, as c' and c^2 , which are

secured together in any suitable manner to form a truncated ellipsoid, as will be clearly seen from an inspection of the several figures of the drawings; but of course it will be evident that the said receptacle may be of any other desirable configuration. Said shells c' and c^2 form the two sides of said receptacle and are provided with outwardly-extending plate-like projections c^3 and c^4 , which 10 form with the upper and preferably curved edges a^7 of the frame or support a . When the said receptacle c is placed between the two side pieces a' and a^2 of the frame or base a , said projections c^3 and c^4 will rest upon the edges 15 a^7 and can be securely fastened thereto by means of screws c^5 or in any other well-known manner.

As will be seen from Figs. 1, 2, and 3, the front and back of the frame a may be suitably cut away to form the curved edges a^8 , which snugly fit the contour of the receptacle c and thereby form a complete joint at the junction of the frame and said receptacle to greatly enhance the beauty of the whole device.

In the lower portion of the back of the frame or base is a horizontal slot or opening a^9 to receive a plate d , which plate can be placed on a surrounding rim or flange a^{10} in said 30 frame, said plate d being provided with an offset d' , whereby it is held in place in the frame, and also has a notch or catch d^2 , whereby the plate d is capable of being sufficiently raised to permit its withdrawal from said 35 frame or base of the device for the purposes of cleaning.

As will be seen from Figs. 5 and 6, the powder-receptacle c , hereinabove mentioned, is provided with a suitably-placed outlet-opening c^6 and has an opening in the top, which can be closed by means of any well-known form of lid or cover c^7 . Extending into a pair of oppositely-placed holes c^8 in the sides of said receptacle are a pair of bent and pointed 45 portions e' and e^2 of a fork e , said fork having the curved parts e^3 and e^4 thereof adapted to be movably arranged between the outer surfaces of the sides of the receptacle c and the inner surfaces of the frame or base a . Below 50 said receptacle c said fork is formed with a part e^5 , which extends beneath the rest a^6 in the opening a^4 of the front of the frame or base a , and e^5 is a suitably-curved plate connected with said fork e , substantially as illustrated, said plate corresponding to the contour 55 of the lower edge of said receptacle c and being in sliding contact with said edge and adapted to normally close the outlet-opening c^6 in said receptacle.

As previously stated, the pointed portions e' and e^2 of the fork e extend into and through holes c^8 in the sides of the receptacle c , and within said casing and secured to said pointed portions e' and e^2 is a wooden or other suitable arbor or shaft f , which is provided with 60 suitably-disposed bristles f' , that terminate in close proximity to the inner surface of the

said receptacle c . Said arbor or shaft f is also provided with a suitable pin or screw f^2 , to which is attached one end of a suitable 70 spring, as f^3 , the opposite end of said spring being attached to an eye or other fastening means c^9 in the receptacle c ; but it will be understood that this arrangement of the spring is not essential, and any other arrangement 75 and other suitable form of spring may be employed, if desired.

The operation of the several parts of the device is as follows: The brush b is placed, with its bristles extending upwardly, upon 80 the rest a^6 , and the end of the brush pushed against the part e^5 of the fork e . Said fork is thus caused to move from its normal position (indicated in Figs. 4 and 5) to the position illustrated in Fig. 6. At the same time the 85 slide e^6 is removed from the outlet-opening c^6 in the receptacle c , and the arbor or shaft f is partially rotated. This action causes the bristles f' to brush the fine powder directly over the outlet-opening c^6 and forces the powder through said opening, from which is distributed upon the bristles of the brush b . During this action the spring f is distended, and while the brush b is being withdrawn from within the frame or base a the said 95 spring f causes the movable parts of the device to return to their normally-inoperative positions and the plate e^6 to again close the outlet-opening c^6 . Thus it will be seen that during the forward and outward movements 100 of the brush b upon the rest a^6 in the frame a the powder will be distributed over the entire surface of the bristles of the brush in just the desired quantity and without any danger of spilling or wasting the powder. 105 The plate d in the bottom of the frame or base serves to catch the smaller particles of powder that may be accidentally spilled, said plate being capable of removal, so that it can be cleaned.

The operations of the several parts of the device are very simple and effective for the purposes for which they are intended, and a neat, cheap, and ornamental powder-distributing device is produced which is very convenient when in use.

I am aware that changes may be made in the several arrangements and combinations of parts without departing from the scope of my invention. Hence I do not limit myself 120 to the exact arrangements and combinations of the parts herein described, and illustrated in the drawings.

Having thus described my invention, what I claim is—

1. In a powder-distributer, the combination, with a closed frame or base having an opening for the reception of a brush, of a powder-receptacle in said frame, having a discharge-opening, means connected with said 130 receptacle operating to normally close said discharge-opening, and open the same, when the brush is inserted in the opening in said frame or base, and an oscillating brush in

said powder-receptacle, and a spring connected with said brush to cause the return of said brush to its normal position over said discharge-opening, and also, to cause the 5 closing of said opening upon the withdrawal of the brush previously inserted in the opening of the base or frame of the distributor, substantially as and for the purposes set forth.

10 2. In a powder-distributer, the combination, with a closed frame or base having an opening for the reception of a brush, of a powder-receptacle in said frame, having a discharge-opening, an oscillatory slide connected with said powder-receptacle, means 15 for operating said slide when the brush is inserted in said opening in the frame or base, and an oscillating brush in said powder-receptacle, and a spring connected with said brush to cause the return of said brush to its 20 normal position over said discharge-opening, and also, to cause the closing of said opening upon the withdrawal of the brush previously inserted in the opening of the base or frame 25 of the distributor, substantially as and for the purposes set forth.

3. In a powder-distributer, the combination, with a closed frame or base having an opening for the reception of a brush, of a 30 powder-receptacle in said frame, a fork-like frame pivoted to said receptacle, comprising a pair of pointed portions extending into and through holes in the sides of said receptacle, said receptacle having a discharge-opening, 35 curved parts e^3 and e^4 and a part e^5 connected with said fork-like frame, a curved plate or slide e^6 on said fork-like frame, adapted to normally close said discharge-opening and to be removed therefrom when the brush is inserted in said opening in the frame or base, 40 an arbor or shaft connected with said pointed portions of said fork-like frame in said receptacle, and a brush or brushes on said arbor or shaft, substantially as and for the purposes 45 set forth.

4. In a powder-distributer, the combination, with a closed frame or base having an opening for the reception of a brush, of a powder-receptacle in said frame, a fork-like

frame pivoted to said receptacle, comprising 50 a pair of pointed portions extending into and through holes in the sides of said receptacle, said receptacle having a discharge-opening, curved parts e^3 and e^4 and a part e^5 connected with said fork-like frame, a curved plate or 55 slide e^6 on said fork-like frame, adapted to normally close said discharge-opening and to be removed therefrom when the brush is inserted in said opening in the frame or base, an arbor or shaft connected with said pivoted 60 portions of said fork-like frame in said receptacle, a brush or brushes on said arbor or shaft, and a spring for causing the return of the movable parts to their initial positions, substantially as and for the purposes set 65 forth.

5. In a powder-distributer, the combination, with a frame or base, having a rest for the reception of a brush, of a powder-receptacle in said frame, having a discharge-opening, an oscillatory brush in said powder-receptacle, a slide arranged over said discharge-opening, means for operating said slide, when the brush is forced against said means, 70 consisting, of a pivoted fork-like frame to which 75 said slide and said oscillatory brush are attached, substantially as and for the purposes set forth.

6. In a powder-distributer, the combination, with a frame or base, having a rest for 80 the reception of a brush, of a powder-receptacle in said frame, having a discharge-opening, an oscillatory brush in said powder-receptacle, a slide arranged over said discharge-opening, means for operating said slide, when 85 the brush is forced against said means, consisting, of a pivoted fork-like frame to which said slide and said oscillatory brush are attached, and a spring for causing the return of the movable parts to their initial position, 90 substantially as and for the purposes set forth.

In testimony that I claim the invention set forth above I have hereunto set my hand this 12th day of November, 1897.

CLEMENT C. CLAWSON.
